UNITED STATES PATENT OFFICE.

WILLIAM J. McBRIDE, OF PHILADELPHIA, PENNSYLVANIA, ASSIGNOR TO HOFFMAN-CORR MANUFACTURING COMPANY, OF PHILADELPHIA, PENNSYLVANIA.

DESIGN FOR A CAP FOR HAMMOCK SPREADER ENDS.

40,369.

Specification for Design.

Patented Nov. 23, 1909.

Application filed August 31, 1909. Serial No. 515,546. Term of patent 3½ years.

To all whom it may concern:

Be it known that I, WILLIAM J. McBRIDE, a citizen of the United States, residing at Philadelphia, in the county of Philadelphia and State of Pennsylvania, have invented a new, original, and ornamental Design for a Cap for Hammock Spreader Ends, of which the following is a specification, reference being had to the accompanying drawing, forming part thereof.

Figure 1, is a perspective view of a cap

for hammock spreader ends showing my new design, Fig. 2, is a view in side elevation thereof, and Fig. 3, is a view in front elevation of Fig. 2.

I claim:

The ornamental design for a cap for hammock spreader ends, as shown.

WM. J. McBRIDE.
